UNITED STATES PATENT OFFICE.

BENJAMIN KUGLER, OF CHICAGO, ILLINOIS.

DESIGN FOR AN ANCHORAGE FOR WINDOW-CLEANERS' HARNESS.

Application filed April 13, 1926. Serial No. 17,267. Term of patent 7 years.

To all whom it may concern:

Be it known that I, BENJAMIN KUGLER, a citizen of the United States, residing at Chicago, in the county of Cook and State of Illinois, have invented a new and original Design for Anchorage for Window-Cleaners' Harness, of which the following is a specification, reference being had to the accompanying drawing, forming part thereof.

Figure 1 is a perspective view of my anchorage for window cleaners' harness,
Figure 2 is a side view thereof,
Figure 3 is an end view thereof.

I claim;

The ornamental design for an anchorage for window cleaners' harness, as shown.

BENJAMIN KUGLER.
